INVENTOR

William B. Rumbaugh,

ATTORNEY

UNITED STATES PATENT OFFICE.

WILLIAM B. RUMBAUGH, OF BELLINGHAM, WASHINGTON.

RAIL JOINT.

Application filed December 23, 1922. Serial No. 608,756.

To all whom it may concern:

Be it known that I, WILLIAM B. RUMBAUGH, a citizen of the United States, residing at Bellingham, in the county of Whatcom and State of Washington, have invented certain new and useful Improvements in Rail Joints, of which the following is a specification.

This invention relates to rail joints.

One of the main objects of the invention is to provide a joint of simple construction and operation having releasable means for locking the securing spike in operative position. A further object is to provide a joint having an element adapted to act as a reinforcing member. Further objects will appear from the detailed description.

In the drawings:

Figure 1 is a top plan view of the invention as applied;

Figure 2 is a section taken on the line 2—2 of Figure 1;

Figure 3 is a detail perspective view of the locking means.

Figure 4 is a top plan view of the plates showing the same applied to a fragment of a tie, the rail being shown in dotted lines.

The rails 1 are of usual construction and are supported by the ties 2. At each side of the rail, on each tie, is secured a rectangular plate 3 which is provided at each end with an integral downwardly extending flange 4. The tie 2 is provided with a recess 5 beneath this plate, the plate constituting a cover for this recess. At each end of the plate a heavy strip 6 of rubber, or other suitable resilient material, is interposed between the tie and the underface of the plate.

The plate 3 is provided with a rectangular aperture which receives the shank 7 of the usual securing spike 8 the head of which engages over the base flange 1^a of the rail 1 in the usual manner. This spike is provided with a cut out or recess 9 in one edge. This recess is adapted to snugly receive a heavy bar spring 10 which is slidably mounted in brackets 11 and 12 supported from the inner face of plate 3. These two brackets are in alinement transversely of the tie and are positioned at either side of the spike. The spring 10 is provided at one end with an integral rectangularly disposed arm or hook 13. This hook is adapted, when the spring is in operative position, to engage into a slot 14 formed in one arm 15 of an angle bracket

16 secured to the tie at the end of recess 5 remote from bracket 11. At the other end the spring is bent over at right angles to provide an integral finger 17. The plate 3 is provided with an aperture 18 positioned above and to one side of finger 17, and with a second aperture 19 above, and adjacent the bracket 12. These two apertures are each adapted to receive a bar for operating the locking mechanism.

In using my invention a plate 3 is mounted at each side of and under the rail 1 and projecting outwardly from the base flange 1^a thereof. A spike 8 is then inserted through the plate and is driven tightly into the tie 2. This spike passes inside of the spring 10 and, when the spike has reached its lowest position, the spring will be forced into the recess 9 by its resiliency. During this operation the hook member 13 of the spring is out of engagement with the slot 14 in the angle bracket 16 and the spring 10 is moved longitudinally of recess 5 so as to bring the tapered portion 10^a of the spring below the opening of plate 3 through which the spike is inserted. After the spike has been driven firmly into tie 2 a bar is inserted through aperture 18 of the plate so as to engage behind finger 17, and the spring is then forced toward the slot 14 in the angle bracket 16. As the spring is moved in this direction the tapered portion 10^a exerts a wedging effect on the spike so as to force it more tightly into engagement with the base flange of the rail. When the spring has been moved into its full operative position the hook member 13 engages through the slot 14 of angle bracket 16 thus securely locking the spring against longitudinal movement. For this purpose the angle bracket is placed slightly out of alinement with the brackets 11 and 12 so that, as the spring is moved into operative position, the hook member 13 will engage the inner face of arm 15 so as to force the end portion of the spring inward under pressure.

As soon as hook member 13 is brought into register with the slot 14 it is forced into the same. When it is desired to release the spike, a bar is inserted through aperture 19 of plate 3 in front of spring 10. The end portion of the spring is then forced laterally by means of this bar. This releases the spring from angle bracket 16 so that, by inserting a second bar through aperture 18 in front of finger 17 the spring can be moved

longitudinally into inoperative position so as to release the spike 8. In moving the spring into operative position a bar will be placed in front of the spring being inserted 5 through the aperture 19, so as to move the spring into proper engagement with the spike.

The spring serves to effectually prevent the spike from being drawn out of tie 2 thus 10 eliminating all possibility of spreading of the rails.

What I claim is:—

1. In rail securing means, the combination of a tie, a rail supported thereby, a plate secured on the tie, said tie being provided with a recess beneath the plate, a spike passed through the plate and engaging with the base flange of the rail, said spike being provided with a recess intermediate its ends, 20 and engaging into the tie, a pair of brackets carried by the plate and in alignment transversely of the tie, a spring slidably mounted in said brackets and adapted to engage into the recess of the spike so as to lock the same, 25 against movement, and means for preventing longitudinal movement of the spring.

2. In rail securing means, the combination of a tie, a rail supported thereby, a plate secured on the tie, said tie being provided with 30 a recess beneath the plate, a spike passed through the plate and engaging over the

base flange of the rail, said spike being provided with a recess in one side, a pair of brackets carried by the plate and in alignment transversely of the tie, a bar spring 35 slidably mounted in said brackets and adapted to engage into the recess of the spike, said bar spring having one end portion tapered whereby a wedging effect is exerted on the spike as the spring is moved into operative position so as to force the spike downward, and means mounted within the recess of the tie and engaging with the spring for locking the spring against longitudinal movement.

3. In a rail securing means, the combination of a tie, a rail supported thereby, a tie plate disposed on the tie, said tie being provided with a recess beneath the plate, a spike passed through the plate and engaging over 50 the base flange of the rail, brackets carried by the plate and mounted within said recess, and means slidably supported by the brackets and disposed in the recess for engaging the spike to prevent movement of 55 the same.

In testimony whereof I affix my signature in presence of two witnesses.

WILLIAM B. RUMBAUGH.
